Primary Examiner — Ricky Pham(74) *Attorney, Agent, or Firm* — Brent M. Burningham(57) **CLAIM**

The ornamental design for bread toaster spikes, as shown and described.

DESCRIPTION

FIG. 1 is an upper perspective view of an embodiment of the bread toaster spikes;

FIG. 2 is a lower perspective view of the bread toaster spikes shown in FIG. 1;

FIG. 3 is an upper perspective view of another embodiment of the bread toaster spikes;

FIG. 4 is an upper perspective view of yet another embodiment of the bread toaster spikes;

FIG. 5 is an exploded view of the bread toaster spikes shown in FIG. 1;

FIG. 6 is a top view of the bread toaster spikes shown in FIG. 1;

FIG. 7 is a right side view of the bread toaster spikes shown in FIG. 1, which view is identical to the left side view;

FIG. 8 is a front view of the bread toaster spikes shown in FIG. 1, which view is identical to the rear view;

FIG. 9 is a bottom view of the bread toaster spikes shown in FIG. 1; and,

FIG. 10 is the cross-section view of the bread toaster spikes, along the plane shown in FIG. 6.

The broken lines shown in the figures are for illustrative purposes only and form no part of the claimed design.

1 Claim, 5 Drawing Sheets(56)
